UNITED STATES PATENT OFFICE.

RALPH F. KNIGHT, OF BEVERLY, MASSACHUSETTS, ASSIGNOR TO UNITED SHOE MACHINERY CORPORATION, OF PATERSON, NEW JERSEY, A CORPORATION OF NEW JERSEY.

MACHINE FOR OPERATING UPON SHOE-SOLES.

1,373,564.

Specification of Letters Patent.

Patented Apr. 5, 1921.

Application filed November 30, 1917. Serial No. 204,637.

To all whom it may concern:

Be it known that I, RALPH F. KNIGHT, a citizen of the United States, residing at Beverly, in the county of Essex and State 5 of Massachusetts, have invented certain new and useful Improvements in Machines for Operating Upon Shoe-Soles; and I do hereby declare the following to be a full, clear, and exact description of the invention, such 10 as will enable others skilled in the art to which it appertains to make and use the same.

The present invention relates to machines for operating upon soles before their incorporation in a boot or shoe, and more particularly to the sole locating devices employed in connection with such machines.

One object of the present invention is to provide an improved form of gaging mechanism which contacts with the side of a sole 20 to position the latter both laterally and longitudinally with relation to the operating instrumentalities.

Sole blanks of different styles may vary 25 considerably in their outline but in all sole blanks that portion of the curved contour adjacent the junction of the shank and forepart of the sole approximates an S curve. According to the present invention this portion 30 of the sole edge is utilized to locate the sole in the proper position relative to the sole molds or other instrumentalities. A feature of the present invention, then, contemplates the provision of a sole gage having three separated and aligned points which 35 are constructed and arranged to simultaneously contact with the curved contour of the sole edge adjacent the junction of the shank and forepart.

With this construction, given any particular shape of sole blank and the proper 40 adjustment of the gage, there is only one position of the blank in which all three points of the gage will contact with the edge of the sole. It follows, then, that after 45 the gage has been preliminarily adjusted to locate any desired style of sole blank relative to the forms, all other blanks of the same shape will be located in identically the 50 same position with relation to the forms if the blanks are properly positioned to

cause all three points of the gage to contact with the sole edge.

The gage has especial utility in connection with the locating of block soles as the S 55 curve bounding the sole at the junction of the shank and forepart consists of two arcs of equal radii with the point of tangency of the arcs coincident with the point of inflection of the curve. These curves are of a 60 uniform size independently of the size of the sole and the point of inflection of the curve bears a fixed relation to the opposite ends of the sole blank. A further feature 65 of the invention contemplates the provision of a sole gage having three separated and aligned points of contact spaced equidistant from one another to locate the center point of the gage opposite the point of inflection of the curve adjacent the junction of the 70 shank and forepart of the sole.

In the case of block soles a single adjustment of the gage will ordinarily serve to locate all sizes of soles with relation to the 75 same set of molds as the increase in length of the soles is secured by the addition of equal increments to opposite ends of the blanks.

In order to properly locate the soles with respect to various styles of molds and to 80 permit the molding of sole blanks of different shapes, a further feature of the invention consists in the provision of means for adjusting a gage of the three point type 85 both longitudinally and angularly of the sole blank and for retaining the gage in adjusted position.

Still further features of the invention consist in certain novel features of construction, combinations and arrangements of 90 parts hereinafter described and claimed, the advantages of which will be apparent to those skilled in the art from the following description.

In the accompanying drawings illustrating the preferred form of the invention, Figure 1 represents a plan view, partly in section, of the improved gaging mechanism as applied to a sole molding machine; Fig. 2 is a side elevation of the mechanism shown 100 in Fig. 1; Fig. 3 is a detail upon an enlarged scale illustrating a plan view, partly in sec-

tion, of certain portions of the gaging mechanism; Fig. 4 is a detail showing a side elevation of that portion of the mechanism shown in Fig. 3; Fig. 5 is a detail illustrating a section of the dial and operating connections taken at right angles to the section shown in Fig. 3; and Fig. 6 is a detail showing a vertical section of the detachable connection for the gage rod.

- 10 The present invention is embodied in a sole molding machine of the usual type, comprising a sole supporting mold 10 adapted to coöperate with the usual pressing mold (not shown) and secured to a mold 15 slide 11 which reciprocates in a head 12. It is essential that the sole shall be located in a certain definite position with relation to these two forms dependent upon the shape of the sole and the style of the form.
- 20 According to the present invention the position of the sole relative to the forms is accurately determined by a single gage which contacts with the side of the sole adjacent the junction of the shank and forepart and 25 serves to locate the sole both laterally and longitudinally of the forms. Block soles have substantially the shape shown in the drawings in which opposite sides of the shank and forepart, respectively, are bounded by straight lines connected adjacent the junction of the shank and forepart by S curves. As shown in the illustrated embodiment of the invention, this S curve consists of two arcs of equal radii with the 30 point of tangency of the arcs coinciding with the point of inflection of the curve, which is located in a certain fixed relation to the opposite ends of the sole independently of the size of the sole blank. The sole gage 35 comprises essentially three separated and aligned points of contact, spaced equidistant from one another and adapted to engage simultaneously with three points on the curved sole edge. According to this construction, then, the center point of the gage 40 when the sole is positioned properly with respect to the gage is located opposite the point of inflection of the curve.
- 45 As shown clearly in the drawings, the gage comprises a bar 15 having three ribs or lugs 16, 17 and 18, which form the contact points. These lugs are spaced equidistant from one another and are adapted to rest upon the surface of the lower mold and contact with the edge of a sole, approximately as shown. According to the usual practice, the sole is moved longitudinally until all 50 three of the contact points engage with the edge when, if the proper adjustments of the gage have been made, the sole should be located properly with respect to the molds. It will be obvious that there can be only one position in which the sole edge contacts with all of the gaging points and that in this 55 position the sole is located both laterally and

longitudinally with respect to the molds. The gaging points are spaced a sufficient distance from one another to cause them to engage with a substantial length of the sole edge and insure the proper locating of the sole.

In order to provide both an angular and longitudinal adjustment of the gage the bar 15 is fulcrumed upon a pin 20 connected to a slide 21. The slide 21 is adjustably supported upon a rod 22 extending longitudinally of the form and provided with teeth 23 which are engaged by a pawl 24 loosely fulcrumed upon the pin 20 and adapted to retain the slide 21 in adjusted position relative to the rod 22. The pawl 24 is provided with a tail 25 engaged by a screw 26 which is threaded in a boss 27 formed upon the bar 15. This screw, when adjusted so that the end contacts with the pawl, retains the latter in engagement with the teeth 23 to hold the slide in adjusted position, and in addition determines the angular position of the bar 15 with relation to the slide. For example, after the screw 26 is adjusted to hold the pawl 24 in engagement with the teeth 23, a further adjustment of the screw swings the bar 15 about the fulcrum 20. The bar is yieldingly restrained against outward swinging movement about the fulcrum 95 by a spring 28 which connects the outer end of the bar with the slide 21. As shown clearly in Figs. 2 and 3, the opposite ends of the spring are connected, respectively, to the lug 18 and a pin 30 depending from the under side of the slide 21. In order to gage both the longitudinal and angular position of the gage the rod 22 is provided with a series of graduations and the bar 15 has a graduated indicator 32 secured to the outer 100 end through a screw 33. By noting the position of the slide relative to the graduated rod 22 and the position of the graduated indicator 32 with relation to the rod, both the longitudinal and angular position of the 105 slide may be determined.

The sole gage is automatically moved into an inoperative position prior to the movements of the forms into pressing position by mechanism similar to that disclosed in 110 the patent to Heys No. 1,222,866, dated April 17, 1917. According to this construction the rod 22, which extends longitudinally of the form, is fulcrumed at the end opposite from the gaging device upon the mold 120 slide 11. As shown in Figs. 1 and 2 of the drawings, a bracket 35 is secured to the mold slide and carries a vertical rock shaft 36 in which the end of the rod is adjustably secured. The opposite end of the rod, or 125 that which carries the gage, is connected with a cam member 37 supported from the frame of the machine and having a receding portion 38 which permits the gage to swing away from the mold 10 upon a horizontal 130

movement of the mold slide to carry the mold 10 into alinement with the pressing mold. The end of the rod 22 is yieldingly retained in engagement with the cam 37 by a spring 40 which is connected between a fixed arm 41 formed upon the bracket 35 and an arm 42 connected to move with the rod 22. This spring 40 normally tends to swing the rod 22 away from the mold and maintains the free end of the rod in contact with the cam 37.

The importance of the angular adjustment of the sole gage will be apparent to those skilled in the art when it is considered that the slope of that portion of the sole edge with which the gage contacts varies not only in soles of different style and shape, but with soles of different sizes. The fulcrum of the rod 22 is so located with respect to the gage that the change in the angular position of the gage, due to a lateral adjustment of the cam 37, approximates the difference in slope of the sole edge for the smaller sizes of soles so that, in the normal operation of the gaging device upon block soles, the adjustment of the gage for different sizes may be secured merely by a lateral adjustment of the cam 37.

The cam 37 is secured to the outer end of a rod 45 slidingly supported in a head 46 secured to the frame of the machine. The rod 45 is adjusted through a rotary cam disk 47 provided with a spiral cam slot 48 which receives a pin 49 secured to the end of the rod 45. Thus by rotating the cam disk 47 the cam 37 may be moved toward or from the form to secure the proper lateral adjustments of the sole gage when in operative position. It has been found that different styles of molds of the same size require a different adjustment of the sole gage. To this end it is advisable in molding any particular style of sole to find the proper adjustment of the gage for that style and to set the indicating dial in accordance with this adjustment. Thereafter the proper adjustments of the gage for different sizes of the same style may be secured by turning the dial until the proper size is indicated. As shown in the drawings, a dial 50 is provided with an inclined face 51 divided into twenty equal divisions and properly numbered, and the periphery of this dial is provided with a series of slots 52 spaced equidistant from one another and adapted for the reception of a pin 53, which is secured to a disk 54. The disk 54 is formed integral with the cam disk 47 and is connected thereto by means of a hub 56. Coöoperating with the dial is a stationary indicator member 58 which comprises a plate secured to the end of an overhanging arm 60 supported at its opposite end upon the bracket 46. This in-

dicator member is properly marked from AA to EE, indicating widths of soles from the narrowest to the widest. It will be obvious that when the pin 53 is received in one of the slots 52 of the dial, the latter will be connected directly to the cam disk 47 and a rotation of the dial will then adjust the sole gage laterally. In order to permit an independent rotation of the dial relative to the cam disk to secure the initial adjustment of the dial, the latter is loosely mounted upon a sleeve 61, forming an extension of the hub 56 and journaled upon a stud 62 secured in the bracket 46, as shown clearly in Fig. 3. The dial is normally retained in position to cause the pin 53 to enter one of the slots by a spring 63 received in a recess formed in the dial and interposed between the dial and a collar 64 secured to the sleeve 61 through a pin 65, as shown clearly in Figs. 3 and 5. With this construction, by retracting the dial so that the pin 53 is disengaged from one of the recesses 52, the dial may be freely rotated without rotating the cam disk 47 to properly adjust the dial for any given position of the sole gage. In order to prevent the rotation of the dial from being communicated to the cam disk when the two are disconnected, a friction washer 66 is interposed between the collar 64 and a head 67 formed upon the end of the stationary stud 62.

According to the usual operation, when it is desired to mold a new or different style of sole the sole gage is first adjusted properly to locate the sole relative to the molds and after this adjustment of the gage has been secured the dial 50 is turned until the proper number upon the dial registers with the proper letter upon the indicator member so that the reading on the dial and indicator member corresponds with the actual size of the sole which is being molded. In this position of the dial the pin 53 will register with one of the recesses formed in the periphery of the dial. For example, when the dial as shown in the drawings indicates that the sole being molded is an 8D, the pin 53 may be received in the recess corresponding to 20 on the dial. After this preliminary adjustment of the sole gage and dial has been made, all of the varying sizes of soles may be properly located relative to the molds by a simple turning of the dial to cause the indications of the length and width to register properly with one another. With this construction it is obvious that if at any future time it is desired to mold this same style of sole again the adjustment of the gage can be secured by making notations relative to the angular and longitudinal positions of the gage, as well as the position of the pin 53 relative to the dial.

In order to permit the gage to be swung into an inoperative position when the lower mold is in a position of presentation the cam 37 is supported in such a manner that it may be swung out of the way when desired. To this end the cam is provided with a hub 70 having a shoulder 71 which engages with a corresponding shoulder 72 formed upon a support 73. A pin 74 passes through the hub 70 and is secured in the support 73. The cooperating shoulders of the hub and support are normally retained in contact by a spring 75 surrounding the pin 74 and pressing down upon the hub to retain the latter in the position shown in Fig. 4. When it is desired to swing the cam out of the way, the hub is merely lifted against the pressure of the spring until the shoulder 71 clears the shoulder 72 when the cam may be swung bodily to permit the movement of the sole gage into an inoperative position.

The gage may be easily removed from the machine by detaching the rod 22 from the hub 80 in which it is received. To this end the rod is provided with a groove or slot 82 which is adapted to receive a spring pressed ball 83. The ball is mounted within the hollow bore of a tubular extension 84 and is engaged by a spring 85 interposed between the ball and a plug 86 threaded in the upper end of the extension 84. The arm 42 is provided with a flat base portion 87 which is held between the hub 80 and the bracket 35, as shown clearly in Figs. 2 and 6. In order to prevent the arm from turning relative to the hub 80 the base portion 87 is provided with an upwardly turned flange 89 which engages with the side of the hub, as shown clearly in the drawings. The shaft 36 is retained in the position shown in the drawings through a collar 90 secured to the shaft on the opposite side of the bracket from the hub 80. It will thus be observed that with this construction the rod 22 together with the arm 42 and the hub 80 are locked together. In order to maintain the rod 22 against a turning movement in the hub 80 a rectangular collar 92 is secured to the rod and is designed to engage with the flat base portion 87 when the rod is in position, as shown clearly in Fig. 2.

In order to provide a relatively quick and substantial adjustment of the sole gage, for example to change the latter from men's to women's work or vice versa, the end of the rod 22 is provided with a rectangular plate 77 which is connected to the rod through a fastener 78 so that it is capable of assuming either the position shown in Fig. 4 or a position in which the short side of the plate contacts with the cam 37. It will be obvious to those skilled in the art that this plate serves to vary the position of the sole gage for the same adjustment of the cam 37 and in consequence provides a quick and convenient

means for securing a coarse adjustment of the gage.

While it is preferred to employ the specific construction and arrangement of parts shown and described, it will be understood that this construction and arrangement is not essential except so far as specified in the claims, and may be changed or modified without departing from the broader features of the invention.

The invention having been described, what is claimed is:

1. A sole molding machine comprising a sole supporting mold and a gage having three separated points of contact adapted to simultaneously contact with the curved contour of the sole edge at one side and locate the sole both laterally and longitudinally in a predetermined position.

2. A sole molding machine comprising a sole supporting mold and a gage having three separated and aligned points of contact adapted to simultaneously contact with the curved contour of the sole edge at one side and locate the sole in a position predetermined by the gage.

3. A machine for operating upon shoe soles, comprising a gage having three separated points of contact adapted to simultaneously contact with the curved contour of the sole edge adjacent the junction of the shank and forepart, and means for adjusting the gage angularly.

4. A machine for operating upon shoe soles, comprising a gage having three separated points of contact adapted to simultaneously contact with the curved contour of the sole edge adjacent the junction of the shank and forepart, and means for adjusting the gage angularly and longitudinally.

5. A sole gage having three separated points of contact spaced equidistant from one another and adapted to simultaneously contact with the curved contour of the sole edge at one side to position the sole both laterally and longitudinally.

6. A machine for operating upon shoe soles comprising a sole gage, a cam for adjusting the gage, connections between the cam and gage, an indicating dial, and means for normally locking the dial to the cam including a disk connected to the cam, a pin projecting from the disk, a flanged hub upon the dial having a series of notches formed in the periphery, and a spring received within the dial and normally tending to move the dial toward the disk to cause the pin to enter one of the notches in the periphery.

7. A sole molding machine, comprising a sole supporting mold, a rod extending substantially lengthwise of the mold, a head supported upon the rod and adjustable longitudinally thereof, means for indicating the position of the head relative to the rod, a sole

gage fulcrumed upon the head and adjustable angularly thereon, and means for indicating the angular position of the sole gage relative to the rod.

5 8. A sole molding machine, comprising a sole gage, a cam for moving the gage into and out of operative position, means for adjusting the cam to vary the position of the gage, and connections between the gage and cam for adjusting the gage to change the position of the gage relative to the cam.

10 9. A machine for operating upon soles comprising a sole mold, and a gage for positioning the sole in a predetermined relation 15 with respect to the mold having three separated points of contact adapted to simultaneously contact with the curved contour of the sole edge at one side.

10 10. A sole molding machine, comprising 20 a mold, a rod fulcrumed at one end and extending lengthwise of the mold, means for adjusting the angular position of the rod, a

head adjustable longitudinally of the rod, and a sole gage pivoted to the head and adjustable angularly thereof.

25

11. A sole molding machine, comprising a rod having a plurality of teeth formed thereon, a head slidably supported upon a rod, a pawl carried by the head and adapted to engage with the teeth, a sole gage pivoted upon the head, a set screw threaded upon the gage and adapted to contact with the pawl, and means for yieldingly swinging the gage to cause the set screw to maintain the pawl in engagement with the teeth. 30

12. A sole molding machine comprising a sole supporting mold and a gage having three separated points of contact constructed and arranged to contact with the curved contour of a sole edge upon opposite sides 40 of the ball line to locate the sole in a position predetermined by the gage.
